CLAIM

The ornamental design for a personal computer, as shown and described.

DESCRIPTION

FIG. 1 is a perspective view of the personal computer with the front cover opened, showing our new design; FIG. 2 is a front elevational view thereof; FIG. 3 is a rear elevational view thereof; FIG. 4 is a top plan view thereof; FIG. 5 is a bottom plan view thereof; and, FIG. 6 is a left side elevational view thereof. The right side elevational view thereof is symmetrical to the left side elevational view thereof.

FIG. 1

FIG. 6

FIG. 2

FIG. 4

FIG. 3

FIG. 5
